UNITED STATES PATENT OFFICE

JOHN J. CALLAHAN AND WILFRED D. McDERMOTT, OF LYNN, MASSACHUSETTS

CLOSURE FOR COLLAPSIBLE TUBES

Application filed April 23, 1930. Serial No. 446,534.

This invention relates to closures, stoppers, and caps for bottles, collapsible tubes or other containers, and is particularly adaptable for use on collapsible tubes of the type in which dental cream, shaving cream, balms, and other similar materials are packed and dispensed.

It has for its objects, to provide an improved form of stopper or cap of comparative simple construction, composed of a minimum number of parts and therefore inexpensive and simple to manufacture; to avoid the threading of caps; to provide a cap which may be both removed and replaced by a positive side pressure of the thumb against the cap; to provide a self lifting and self sealing construction available for opening from either side, which when the cap is subjected to a side pressure breaks the seal by lifting the cap, provides clearance for the cap in tipping from the container and clearance again in replacement thereon; to provide a cap construction which may be readily and conveniently opened and closed by one hand operation; to provide a construction which at all times firmly holds the cap both in open and closed position; to provide a construction which adequately distances the cap from the outlet when in open position; to provide a combination double seated and sealed construction; to provide a construction adapted to lift the cap and throw it off center during the opening operation; to provide an improved spring construction adaptable to function as a hinge and a specific and positive anchor designed to make the tips of the spring hug the orifices into which they are fitted; to supplement the force which normally tends to position and hold the ends of combination anchor and hinge; to avoid the tendency of the anchor and hinge slipping from the orifices into which it is fitted; and to provide the various other advantages and results made apparent from the following specification.

Referring to the accompanying drawings which form a part of this specification and in which similar letters of reference refer to similar parts throughout the various views, Figure 1 is a view in elevation showing the upper portion of a collapsible tube with the

closure of our invention applied thereto. Figure 2 shows the tube in the same position with the closure tipped to open position. Figure 3 is a view in elevation of the upper portion of the collapsible tube shown in Figure 1 but at right angles thereto, a sectional view of the head being shown. Figure 4 is a view of that portion of the tube shown in Figures 1 and 2, but without the closure. Figure 5 is a side view of the closure or cap. Figure 6 is a sectional view of the cap shown in Figure 5 but at right angles thereto. Figure 7 shows a view of the spring by means of which the closure is hinged and anchored to the tube.

Referring again to the figures, A shows the body of the tube. B shows the head of the tube. C shows the aperture or outlet passage. D shows the shoulders positioned at the base of and on opposite sides of the neck B. E shows the transversely disposed sockets in the shoulders D, into which the angularly arranged pivot pins F of the spring or loop G (shown in Figure 7) are adapted to be seated. H shows a tooth extending from the shoulders D, designed to engage and mesh with the prongs H² and H³ on each side of the closure or cap I. J shows a beveled seat on the neck B designed to fit against the cap at J² and thereby perfect a seal. The top of the neck B is flat at B² and there dimensioned to fit snugly against the gasket B³ preferably made from cork and carried within the cap I. The cap is provided with sectional elevated edges I² and I³ for ready and convenient thumb use in opening and closing the tube. The knob I⁴ and slot I⁵ therein are provided as a bearing place for the center G² of the spring G. The angularly arranged pivot pins F are provided at their terminals with an upwardly turned burr F² designed to prevent the spring G from slipping out of the sockets E. In use, the burrs F² wear a groove at the bottom of the sockets E and the anchorage therein is constantly strengthened.

The closure is removed from the aperture of the tube by exerting a side pressure, as with the thumb, against the sectional elevated edge I³, whereupon the cap I tips, and as it

tilts the square corners on the prongs H bearing on the shoulders D cause the cap to rise up breaking its seal against the neck B of the tube gradually throwing it off center and leaving the cap free to tip to the position shown in Figure 2, the aperture being made by the said movements free and clear for emptying purposes.

While we have illustrated and described a preferred construction for carrying our invention into effect, this is capable of variation or modification without departing from the spirit of the invention. We therefore do not wish to be limited to the exact details of construction herein set forth but desire to avail ourselves of such variations and modifications as come within the scope of the appended claims.

Having thus described our invention we claim as new and desire to secure by Letters Patent of the United States of America:—

1. In combination with a receptacle having a hollow body and an apertured neck extending therefrom, the outer edge of said neck being bevelled and at its top flat, shoulders on opposite sides of said neck, transversely disposed sockets in said shoulders, a cap having recesses therein the inner edge of which is shaped to seat and seal upon said bevelled edge, and having a flat extreme inner surface teeth upon said shoulders adapted to cooperate with said cap, a gasket on said flat inner surface adapted to fit against the top of said neck when said bevelled edge is sealed, and a wire loop extending from the neck over the cap, said loop having angularly arranged pivot pins with a burr on the ends thereof adapted to fit into said transversely disposed sockets.
2. In combination with a receptacle having a hollow body, and an apertured neck extending therefrom, the outer edge of said neck being bevelled and its top flat, shoulders on opposite sides of said neck, transversely disposed sockets in said shoulders, a tooth extending from each shoulder designed to engage and mesh with prongs on each side of the cap next mentioned, a cap the inner edge of which is shaped to seat and seal upon said bevelled edge, and having a flat extreme inner surface, a gasket on said flat inner surface, adapted to fit against the top of said neck when said bevelled edge is sealed, said cap having extending therefrom a pair of prongs adaptable to mesh with said tooth, and a wire loop extending from the neck over the cap, said loop having angularly arranged pivot pins with a burr on the ends thereof adapted to fit into said transversely disposed sockets.
3. In a device of the kind described, a container having a hollow body and an apertured shouldered neck, transversely disposed sockets therein, a double seated cap adapted to fit upon said neck, said cap having spaced

prongs extending therefrom, a wire loop having angularly arranged pivot pins with a burr on the ends thereof, adapted to fit into said transversely disposed sockets and secure the cap to the neck, teeth projected from the shoulders on the container shaped to mesh and function with said prongs to lift the cap and throw it off center as side pressure is applied during the opening operation.

4. In a device of the class described a container having a hollow body and an apertured neck, shoulders upon said neck, a cap adapted to fit upon said neck, said cap having spaced prongs thereon, means for pivotally securing said cap to said shoulders and teeth projecting from said shoulders adapted to mesh and cooperate with said prongs to lift said cap and throw it off center as side pressure is applied during the opening operation.

5. In a device of the class described a container having a hollow body and an apertured neck, shoulders upon said neck, a cap adapted to fit upon said neck, said cap having spaced prongs extending therefrom, a wire loop securing said cap to said neck and teeth projecting from said shoulders upon said container adapted to cooperate with said prongs to lift said cap from said aperture in said neck.

In testimony whereof we affix our signatures.

JOHN J. CALLAHAN.
WILFRED D. McDERMOTT.
